INVENTOR

BY *B.W. Dahn*

ATTORNEY

UNITED STATES PATENT OFFICE.

JOSEPH LEVY, OF TULSA, OKLAHOMA.

SPEAKING TUBE.

Application filed March 4, 1927. Serial No. 172,897.

My said invention relates to a device in the nature of a speaking tube, or what I call a "speakadoor," so arranged that under ordinary conditions it may be closed at both ends thus leaving no opening or apparent break of any consequence in the walls or partitions through which it may at times be desirable to speak. When the device is to be used it can instantly be made open throughout its entire length and after use it can be so manipulated by the user as to close it at both ends and secure it against re-opening. By appropriate painting, etc., it can be made very inconspicuous. It can readily be mounted in any situation where it is to be used and, being extensible, it can be properly positioned regardless of the distance between the walls, partitions, etc., separating the rooms which are to be placed in communication. Such extensibility is, of course, limited but permits considerable range of adjustment and thus does away with any cutting to fit, while it can be made in various sizes to provide for situations beyond the adjustable limit of the preferred or conventional size.

Referring to the drawings, which are made a part of this application and in which similar reference characters indicate similar parts:

Fig. 1 is an elevation of my device,

Fig. 2, an end elevation.

Fig. 3, an elevation of the opposite end, and

Fig. 4, a longitudinal central section.

Referring to the drawings in further detail, numeral 3 indicates partition walls or the opposite sides of a wall to which wall plates 5 and 6 are secured by means of screws 2 or other suitable fastening means. A tube 4 is welded to the wall plate 5 or otherwise secured thereto or may merely abut against the same. Another tube 15 is arranged in similar relation to wall plate

6, the latter tube fitting slidably in tube 4. Doors 7 and 8 are pivoted respectively to the plates 5 and 6 and are connected by a rod 11. A spring 12 is secured at one end to the rod 11 and at the other end to a holder 14

which can be a lug on the plate 5 or may be separate therefrom and fixed to the wall 3, said spring tending to open the doors simultaneously. It will be noted that the

rod is pivotally secured to the doors 7 and 8 at 13 and 10 respectively.

A pivoted catch 1 serves, when turned into the position indicated in Fig. 3, to hold the doors in closed position. A lug 9 coacts with door 8 to prevent the doors from being opened from the outside, said lug fitting in a notch or depression in said door. The "speakadoor" may be installed either in the door casing or in the wall adjacent thereto.

It is thought that the operation of my device will be clear from the foregoing. It will be obvious to those skilled in the art that many changes may be made in my device all without departing from the spirit of my invention, the true scope of which is indicated in the appended claims. In the claims specific terms are used for clearness and not for limitation, it being obvious that my device will serve not only as a speaking tube but, for example, also as a look out, as when it is installed in a door jamb or in a wall adjacent a door. In such a location it is possible for a person on the inside not only to converse with the person on the outside but also to see the latter person.

Having thus fully described my said invention, what I claim as new and desire to protect by Letters Patent is:

1. A speaking tube having doors at opposite ends, and connections independent of the tube from one door to the other for actuating them simultaneously.

2. A speaking tube having doors at opposite ends, connections between said doors, and a spring acting on such connections to move the doors in one direction.

3. A speaking tube having doors at opposite ends, a rod connecting said doors, a spring tending to open said doors, and means for securing the doors in closed position.

4. A speaking tube for use in a wall having aligned openings, said tube comprising telescoping tubular members for convenient assembly, doors at the opposite ends of the tube, and a rod connecting the doors for operating them simultaneously.

In testimony whereof I affix my signature.

JOSEPH LEVY.
